FEED BACK ELIMINATION IN ALTERNATING CURRENT TUBE SETS

Filed March 6, 1928

UNITED STATES PATENT OFFICE

LESTER L. JONES, OF ORADELL, NEW JERSEY

FEED-BACK ELIMINATION IN ALTERNATING CURRENT TUBE SETS

Application filed March 6, 1928. Serial No. 259,453.

This invention relates to radio receiving systems, and relates more particularly to highly sensitive radio receiving apparatus; and has special reference to the provision of means for controlling feed-back in radio receiving circuits employing alternating current sources of supply.

In building sensitive radio receiving systems, that is, receiving systems which have a large amount of radio frequency amplification, one of the most difficult problems to solve is the control or elimination of feed-back of energy from a later stage of amplification to the input circuit of the radio frequency amplifier. This is especially true when the input circuit is of the loop type having minimum decrement. When the input circuit is made very sharply tuned, it requires only the barest trace of amplified energy to create oscillation or signal distortion. The channels through which these distant stage feed-backs, as I term them, occur are great in number and many of them have already been discovered and means devised for closing them.

The present invention relates especially to the type of radio receiving system in which the amplifying tubes have their filaments energized by alternating current and in which the detector tube is of the uni-potential cathode or indirectly heated cathode type. In constructing a sensitive receiver of this type having, for example, six stages of radio frequency amplification preceding the detector, I have discovered new hitherto unsuspected feed-back channels. The prime object of my present invention centers about the provision of means for controlling and for closing these feed-back channels.

To the accomplishment of the foregoing and such other objects as will hereinafter appear, my invention consists in the elements and their relation one to the other, as herein-after more particularly described and sought to be defined in the claims; reference being had to the accompanying drawing which shows the preferred embodiment of my invention, and in which:

Fig. 1 is a wiring diagram of a radio re-

ceiving system embodying the principles of my present invention, and

Fig. 2 is an explanatory wiring diagram of essential parts thereof.

Referring now more in detail to the drawing, and having reference first to Fig. 1 thereof, the radio receiving system to which my inventions are shown applied comprises a radio frequency amplifier having six stages of radio frequency amplification employing electron relays of the three-element type designated R. F. 1 to R. F. 6 inclusive, followed by an electron discharge tube detector designated also Det., the output of which feeds into an amplifier comprising two stages of audio frequency amplification, the first stage consisting of an electron relay tube 1 A. F. and the second stage consisting of a push-pull amplifier embodying two power tubes designated 2 A. F. 1 and 2 A. F. 2, the output of which contains terminals to which the "speaker" is connected.

The radio frequency and audio frequency tubes, in the embodiment of the invention herein shown, are of the usual hot filament type in which the filament is the electron emitter and the detector tube Det. is of the uni-potential cathode type having a filament *f*, an indirectly heated cathode *c*, a grid *g* and a plate *p*. The filament *f* is the heater for the cathode and is energized by alternating current fed to the terminals designated 2.5V.Fil. The filaments of the six radio frequency tubes R. F. 1 to R. F. 6 as well as the filament of the first audio stage 1 A. F. are energized by raw alternating current, these filaments being connected in parallel and to a filament circuit *F* fed from the leads 10 connected to the terminals designated 1.5V.Fil. The filaments of the two tubes of the push-pull amplifier are connected in parallel and are energized by alternating current obtained from a source connected to the terminals designated 5V.Fil. The "dial light" for illuminating the receiver dial is also preferably energized by this source, as clearly shown in the drawing. All of the tube filaments are preferably supplied from different windings on a single transformer, referred to further hereinbelow, which forms part of a

power supply unit for the receiver and which also provides the B and C voltages, the terminals of which are shown in Fig. 1 of the drawing and designated -C, +B Det., +B Int., 5 and +B Max. As will be understood, these designations are descriptive, both quantitatively and qualitatively.

The radio frequency amplifier disclosed embodies a number of my inventions 10 described and claimed in other of my Letters Patent and copending applications. As illustrated, the radio frequency tubes are cascaded by successively tuned and untuned circuits, the tuned stages alternating with the 15 untuned stages, all as described and claimed in my Patent No. 1,620,661, dated March 15, 1927, to radio frequency amplifying system. The untuned stages, as for example the stage intermediate the tubes R. F. 1 and R. F. 2, 20 or intermediate the tubes R. F. 3 and R. F. 4, are constructed preferably as disclosed and claimed in my copending application Ser. No. 182,220, filed Apr. 9, 1927, to amplifying system. Volume adjustment is preferably 25 secured by variably coupling the primary and secondary of the tuned stages, as for example the stages intermediate the tubes R. F. 2 and R. F. 3 and intermediate the tubes R. F. 4 and R. F. 5, as disclosed and claimed in my co- 30 pending application Ser. No. 123,346, filed July 19, 1926, to radio frequency amplifying system. The principles underlying the construction and arrangement of the R. F. amplifier are substantially fully described in these 35 copending applications and Letters Patent; and the constants of the various elements composing this amplifier are further specified hereinafter.

One of the essential objects of my present 40 invention centers around the design of the circuits associated with A. C. tubes of the uni-potential or indirectly heated cathode type. In the embodiment shown herein, this invention is applied to the detector tube Det. 45 but may be applied to A. C. tubes used either for detection or radio frequency amplification purposes. The detector tube Det. has for its input a transformer L13, L14 wound bifilarly and including a free section L15 coupled to 50 the grid *g* of the detector tube through a grid condenser C10 and into the cathode *c*. A grid leak R7 is also provided but the grid condenser C10 and grid resistance R7 may be dispensed with at a slight loss of detector 55 sensitivity. This radio frequency transformer L is encased in a separate metal case 12 which, as shown, is grounded at G with the cathode *c* of the detector tube.

I have discovered that in A. C. tubes of this 60 character, there exists some unshielded capacity between the electrodes of the tube, the grid and plate of the tube inducing radio frequency voltages on the heater filament *f* even though the cathode *c* apparently shields the heater from the grid and plate. I have found

that there is some unshielded capacity, as for example in the stem of the tube, in the tube prongs, socket and adjacent lead wires; and with high R. F. amplification the voltages induced on the heater *f* from the grid and plate are sufficient to raise the potential of the heater circuit to a value high enough to create disturbing feed-back effects from the battery eliminator or power apparatus and its associated circuits back to the loop or antenna via the heater or filament supply line, the eliminator case or even the power supply line connected with the eliminator. I have empirically determined that the effects of this unshielded capacity resulting in the undesirable feed-back flow of energy may be controlled by suitably organizing the heater circuit; and more specifically, I have discovered that the addition of the bypass condensers C15 and C16 connected to each side of the heater supply line or circuit 13, 13 and connecting the same to ground potential prevents the passage of radio frequency current out along the heater supply line or prevents the building up of potential above ground (the metal case enclosing the receiver) by providing paths of very low impedance for the radio frequency current from the heater terminals to the case or ground. Preferably I employ two bypass condensers 95 as shown, each of low impedance, the use of the pair of condensers functioning not only for closing the feed-back channel, but also for eliminating a hum, particularly the modulation hum, which modulation hum is due to the modulation of the carrier wave by some inequality in the tube balance.

The heater or filament *f* is preferably conductively grounded at substantially its mid-point and the feed-back control channels are 100 preferably balanced by making the condensers C15 and C16 equal in capacity to a commercial degree of accuracy, as, for example, approximately 5%. In Fig. 2 of the drawing is shown the manner in which the heater 105 is thus conductively grounded, the filament supply line being taken from the secondary 14 of a transformer, the said secondary being provided with a shunt potentiometer 15, the mid-point of which is grounded by the line 16. If only one bypass condenser should be employed, or if the condensers are not made equal in capacity with this construction, the system tends to generate a hum audible in the loud speaker and having a frequency approximately equal to that of the power supply frequency whenever there is present a strong carrier wave. This hum is 110 eliminated by the feed-back control means 115 thus provided.

The grounding of the cathode *c* of the detector tube, and preferably together with the grounding of the separate shielding case 12, is also of essential importance. With this construction I am enabled to devise a simple 120 125 130

- circuit free from external radio frequency feed-backs. The grounding of the cathode in the manner shown greatly reduces the path through which radio frequency currents existing in the detector tube can circulate and thereby reduces the voltages possible from such circulatory currents, and also reduces the magnetic fields which such circulatory currents generate. The provision of the metal case 12 serves to prevent magnetic feed-backs from the R. F. transformer L13, L14, L15 (which transformer has the maximum amount of radio frequency magnetic energy) to other coils and circuit connections at the input end of the system. It also serves to reduce the magnetic coupling to the loop through unavoidable cracks in the enclosing case of the radio system or when the receiver case is open for adjustment.
- While I have shown these inventions applied to the detector tube, the same may be applied, as heretofore stated, to a system of radio frequency tubes of the indirectly heated cathode type. When a plurality of these tubes are used, the filaments of which are connected in parallel circuit, a single pair of condensers corresponding to the condensers C15 and C16 may be employed for the entire filament supply line.
- Where the filament voltage is low, bypassing condensers C15 and C16 may be substituted or replaced by equivalent devices; for such low voltage filaments it becomes practical to substitute, for example, non-inductive resistances of fairly low value for these bypass condensers C15 and C16. This would involve, however, a slight additional power loss due to current in this shunt resistance to the filament. The same substitution of equivalents may be made where the invention is applied to a system of radio frequency tubes of the indirectly heated cathode type. Preferably I provide a condenser C11 shunting the plate *p* and cathode *c* for bypassing radio frequency energy from the primary winding of the audio transformer T1. This condenser is of relatively small capacity, namely, .002 mfd., so as not to shunt out the higher audio frequencies. As a result some radio frequency energy may be found at the lower end of the primary winding of the transformer T1, and this is bypassed to ground by the bypass condenser C14.
- I have found that the filament supply line F for heating the filaments of the radio frequency tubes also provides an undesirable channel for the feed-back of energy from a distant radio frequency stage back to the input, as, for example, the loop L1 of the R. F. amplifier. The existence of this feed-back channel is illustrated in Fig 2 of the drawing, wherein the tube feed-back channels are designated by the phantom condensers K and K'. A flow of feed-back energy may be traced, for example, from the ground G through the coil L13 across the capacity K' of the tube R. F. 6, the energy then flowing in the arrowed direction through the filament line F to the filament of the first tube R. F 1 across the capacity K of said tube to and through the input inductance L1 back to ground G. For controlling and neutralizing this distant stage feed-back flow, the filament supply line F is organized so that the radio frequency energy is balancingly bypassed to ground. This is effected by arranging the filament supply line so that the output and input sides of the radio frequency amplifier are separated from each other by a filter circuit consisting of bypass condensers at the input and output sides of the filament line and of an inductive reactance between them which is inherently provided by the filament leads between the input and output sides of the amplifier.
- More specifically, as shown in Figs. 1 and 2 of the drawing, at each end of the inductive reactance filament circuit F, I place the bypass condensers C17 to C20 inclusive, a pair of condensers C18 and C19 being connected to the input side of the inductive reactance and another pair of condensers C17 and C20 being connected to the output side of the inductive reactance. Preferably the filaments are grounded at their mid-points, this being effected by supplying the line F from the secondary 17 of a transformer T4, the mid-point of which is tapped by the line 18 having a bias resistance 19. With this arrangement, the condensers C18—C19 and C17—C20 are preferably matched in capacity so as to prevent any unbalance of this center tap. These condenser pairs are wired with the shortest possible leads from filament circuit to ground, the ground being the metal case enclosing the complete receiver. The condensers are of relatively high capacity of the order of 1 mfd. each and are of the non-inductive or quick discharge type. The center tapping of the transformer secondary 17 and the equalizing of the condenser capacities is desirable for preventing hum in the receiver output. With this arrangement, referring to Fig. 2 of the drawing, it will be seen that the radio frequency potentials developed at both ends of the inductive reactance filament line F are prevented from reaching the input of the amplifier, the energy being bypassed to ground through the low impedance channels provided therefor.
- A small amount of radio frequency energy may also be carried through the audio frequency amplifier system; and to compensate for this the condensers C12 and C13 are provided, these condensers functioning to bypass this radio frequency energy to ground so as to prevent its issue from the receiver case into the loud speaker from whence it might feed back into the loop aerial L1.

These condensers C12 and C13 are preferably of the order of .005 mfd's. so as not to bypass too much of the higher audio frequencies. The condenser C21 is also wired in the circuit and to ground with the shortest possible leads, and this condenser is of the quick discharge type and of relatively high capacity. It serves to reduce the impedance common to the plate circuits of the radio frequency tubes to a value sufficiently low to prevent feed-back through this channel.

I have also found that some small traces of radio frequency energy may be found in the filament circuit of the power tubes, but this is insufficient in a receiver of the sensitivity shown to produce any appreciable detrimental effect. After all of these feed-back channels are closed, I have found that for certain arrangements of power apparatus and loop some feed-backs might still occur, and I have traced these to magnetic coupling between the loop L1 and another loop consisting of the heater cables to the power supply device and from this back to the receiver through the B and C cable. This feed-back I have found may be avoided by combining these wires or cables in a single trunk or inside a single sheath. The filament wires to each individual tube are preferably transposed by twisting to prevent the production of audio frequency magnetic fields which might be picked up by the first audio transformer or by the detector input transformer.

An example of the various magnitudes or constants of the elements of a radio receiving system built in accordance with the principles of the present invention and showing one of the preferred forms the invention may take, is as follows:

L—1 loop—137 micro-henries

The use and operation of the radio system of my invention and the many advantages thereof will in the main be fully apparent from the above detailed description thereof. It will further be apparent that while I have shown and described my invention in the preferred form, many changes and modifications may be made in the structure disclosed without departing from the spirit of the invention, defined in the following claims.

I claim:

1. In a radio system, a radio frequency amplifier comprising a plurality of radio frequency amplifier tubes arranged in cascade, a circuit for the filaments of said amplifier tubes adapted to be fed by alternating current, the filament circuit between the input and output ends of the amplifier forming an inductive reactance for radio frequency energy, and bypass means connected from each of the ends of said inductive reactance or filament circuit to ground at the input and output ends of the amplifier.

2. In a radio system, a radio frequency amplifier comprising a plurality of radio frequency amplifier tubes arranged in cascade, a circuit for the filaments of said amplifier tubes adapted to be fed by alternating current, the filament circuit between the input and output ends of the amplifier forming an inductive reactance, and mechanism for controlling the flow of an energy feed-back moving via said filament circuit comprising bypass condensers connected from each of the ends of said filament circuit or inductive reactance to ground at the input and output ends of the amplifier.

3. In a radio system, a radio frequency amplifier comprising a plurality of radio frequency amplifier tubes arranged in cascade, a circuit for the filaments of said amplifier tubes adapted to be fed by alternating current, and mechanism for controlling the flow of an energy feed-back moving via said filament circuit comprising low impedance bypass means connected from each of the opposite sides of said filament circuit to ground at both the input and output ends of said amplifier.

4. The combination of claim 1 in which the bypass means comprises a bypass condenser element connected from each side of said filament circuit to ground at both the input and output ends of the amplifier.

5. In a radio system, a radio frequency amplifier comprising a plurality of radio frequency amplifier tubes arranged in cascade, a circuit for the filaments of said amplifier tubes adapted to be fed by alternating current, means for grounding the mid-point of said circuit, and mechanism for controlling the flow of an energy feed-back moving via said filament circuit comprising four substantially equal bypass condensers, said condensers being connected from each side of

said filament circuit to ground at both the input and output ends of said amplifier.

6. In a radio system, an electron discharge tube of the indirectly heated cathode type having grid, plate and cathode electrodes and a separate heater for the cathode, a circuit connected to the heater for supplying alternating current thereto, a potentiometer type resistance connected in shunt to said circuit for conductively grounding said heater at substantially its midpoint, and means for controlling the flow of a radio frequency energy feed-back moving via said heater circuit comprising a pair of substantially equal bypass condensers, one connected between each side of the heater circuit at a point near the tube directly to the nearest possible ground point, and each of said condensers forming a direct low impedance radio frequency path therebetween, so as to substantially eliminate radio frequency potential on the heater with respect to ground.

7. In a radio receiving system, a plurality of radio frequency amplifying tubes and a detector tube arranged in cascade, said detector tube being of the indirectly heated cathode type having grid, plate and cathode electrodes and a separate heater for the cathode, a circuit connected to the heater for supplying alternating current thereto, a pair of substantially equal bypass condensers, one connected from each side of said heater circuit directly to ground and forming a direct low impedance radio frequency path therebetween, a common supply circuit for the filaments of said amplifier tubes, and bypass condensers connected from each of the ends of said circuit to ground at the input and output ends of the amplifier.

8. In a radio frequency multi-stage amplifying system of high gain, a plurality of cascaded tubes at least one of which is an electron discharge amplifier tube of the indirectly heated cathode type having a grid, plate, and cathode electrodes and a separate heater for the cathode, a power supply source of heater current for said tubes, supply circuits from the source to the tubes for supplying current thereto, and means for controlling the flow of a radio frequency energy feed-back moving through capacity channels in said tube and via said supply circuits comprising bypass condenser means connected from said cathode heater at a point adjacent the tube directly to the nearest possible ground point and forming a direct low impedance radio frequency path between the cathode heater and the said nearest ground point, said connection point adjacent the tube being at least nearer the cathode heater than the junction point of the supply source and the supply circuits running from said source to the other tubes of the amplifier, in order to substantially eliminate the radio frequency potential on the heater with respect to ground.

9. In a radio frequency multi-stage amplifying system of high gain, a plurality of cascaded tubes at least one of which is an electron discharge amplifier tube of the indirectly heated cathode type having a grid, plate, and cathode electrodes and a separate heater for the cathode, a power supply source of heater current for said tubes, supply circuits from the source to the tubes for supplying current thereto, and means for controlling the flow of a radio frequency energy feed-back moving through capacity channels in said tube and via said supply circuits comprising a pair of bypass condensers, one connected from each side of said cathode heater at a point adjacent the tube directly to the nearest possible ground point and each forming a direct low impedance radio frequency path between the cathode heater and the said nearest ground point, said connection points adjacent the tube being at least nearer the cathode heater than the junction point of the supply source and the supply circuits running from the source to the other tubes of the amplifier, in order to substantially eliminate the radio frequency potential on the heater with respect to ground.

Signed at New York city in the county of New York and State of New York this 3rd day of March A. D., 1928.
